UNITED STATES PATENT OFFICE.

NOBLE W. HARTMAN, OF TOLEDO, OHIO.

SAFETY-CRANK FOR INTERNAL-COMBUSTION ENGINES.

No. 892,049.

Specification of Letters Patent.

Patented June 30, 1908.

Application filed September 3, 1907. Serial No. 391,001.

To all whom it may concern:

Be it known that I, NOBLE W. HARTMAN, a citizen of the United States, residing at Toledo, in the county of Lucas and State of Ohio, have invented certain new and useful Improvements in Safety-Cranks for Internal-Combustion Engines; and I do declare the following to be a full, clear, and exact description of the invention; such as will enable others skilled in the art to which it appertains to make and use the same, reference being had to the accompanying drawings, and to the letters and figures of reference marked thereon, which form a part of this specification.

My invention relates to a safety crank for starting internal combustion engines such as are commonly used in automobiles and launches, and its object is to provide a device which shall overcome the dangers attending the use of these cranks as commonly constructed and the frequent mishaps which occur when premature explosions or "back firing" take place in the cylinder of the engine and the crank is thrown back against the hands or arms of the operator.

A further object of my invention is to furnish a device of the described character which may be readily applied to the starting cranks of any of these engines now commonly in use.

I attain these objects by means of the devices and arrangement of parts hereinafter described and shown, and illustrated in the accompanying drawings in which,—

Figure 1 is a front-elevation of my device with the crank removed; Fig. 2, a side-elevation showing the crank in place with the frame and escutcheon hereinafter referred to, in section; Fig. 3, a top-plan view of the same showing the engine shaft in section, and Fig. 4, a rear-elevation of the crank detached.

Like numerals of reference indicate like parts throughout the drawings.

In the drawings, 1 is a crank-arm, 2 the handle, and 3 the hub of the crank. Upon the hub is an enlarged disk-like portion 4 having teeth or cogs 5 upon its periphery arranged spirally to the axis of the hub.

6 represents a portion of the frame of an automobile having therethrough an opening 7 adapted for the reception of the extremity of the crank hub.

8 is an escutcheon or ring resting against the outer face of the frame and surrounding the disk-like part 4 of the hub. Rigidly secured to the escutcheon are two inwardly

projecting pins 9 passing through holes 10 in the frame and provided at their inner extremities with heads 11. Between these heads and the frame, and surrounding the pins 9 are interposed spiral springs 12 which hold the escutcheon 8 normally against the outer face of the frame but which permit the escutcheon to be moved laterally outwardly away from the frame.

13—13 are pins which project radially inwardly through the escutcheon or ring 8 and which are rigidly secured in place, forming internal teeth in the ring. These pins at their inner ends are adapted to engage the spiral teeth 5 on the hub.

14 is the engine-shaft which is engaged with the crank-hub in the usual way, or in preferred manner, so that the shaft may be operated forwardly by the hand-crank and so that when the shaft is revolved rapidly ahead by the engine the crank will be disengaged from the shaft. In the present instance, for illustration, the end of the crank-shaft is bored axially, as at 15, to receive a reduced portion 16 on the inner end of the crank-hub. Through this reduced portion passes a pin 17 the projecting ends of which are adapted to engage radial shoulders 18 formed upon the end of the crank-shaft at opposite sides of the bore 15. When the reduced portion of the crank-shaft is inserted into the bore 15, the pins 17 engage the shoulders 18 and the crank and the shaft may now be rotated forwardly together. When the engine starts rapidly ahead, the crank is forced outwardly and out of engagement with the crank-shaft by means of the wedge-like action of the beveled portions 19 on the end of the crank-shaft. Ordinarily if the crank-shaft revolves backwardly instead of forwardly, the shoulder 18 carries the pin 17 with it, causing the crank-arm and handle to deliver a violent blow to anything in their path.

The operation of my device is as follows: Upon the crank being turned in the proper direction the shaft turns with the crank in the usual manner and as above described. Now the pins 13 projecting into the spiral teeth 5 are, by the screw-like action of the teeth, caused to move outwardly away from the frame 10 of the machine, the springs 12 yielding to the outward movement of the escutcheon 8 and the pins 9. While the crank is going in the proper direction the pins 13 slip idly along the outer ends of the teeth or cogs 5. It will be seen that the

spiral teeth now tend to hold the crank in engagement with the engine shaft while the crank is turned forwardly, thus dispensing with the necessity at such time of manually 5 pressing inwardly on the crank. But should a "back-fire" take place the pins 13 instantly engage the spiral teeth 5 and travel in the opposite direction carrying the escutcheon or ring 8 laterally toward and against 10 the frame of the machine. Now, since the pins 13 cannot move inwardly more than, say, a quarter of an inch, the screw-like action of the pins upon the spiral teeth forces the crank-hub outwardly and away from the 15 frame of the machine, instantly pulling the crank out of operative engagement with the engine-shaft. Thus no harm results from the reverse movement of the engine-shaft.

Having described my invention, what I 20 claim and desire to secure by Letters Patent, is—

1. In a device of the described character, an engine-shaft, a hand-crank, means for operatively engaging the crank and shaft for 25 forward rotation, and means for the disengagement of the crank and shaft by the reverse rotation of the shaft, said latter means

comprising a spirally toothed portion on the hub of the crank, a ring surrounding said spirally toothed portion, supports for the 30 ring which permit its lateral movement, internal teeth on the ring adapted for engagement with said spiral teeth, and a spring which holds said internal teeth and said spirally toothed portion in normal engagement. 35

2. In a device of the described character, an engine-shaft, a detachable hand-crank for said shaft, a spirally toothed hub for the crank, a frame-member, a ring surrounding said hub, internal projections upon the ring 40 which engage the spiral teeth of the hub, guide-pins upon the ring which project through the frame-member, and springs which engage said guide-pins and said frame-member and which hold the internal projections upon the ring normally engaged with the spiral teeth of the crank-hub. 45

In testimony whereof I affix my signature in presence of two witnesses.

NOBLE W. HARTMAN.
